TRAFFIC SIGN FOR A SCHOOL ZONE

Richard B. Boone, 2321 Catalo Lane,
Arlington, Tex. 76010

Filed Apr. 29, 1974, Ser. No. 465,203

Term of patent 14 years

Int. Cl. D10—06

U.S. Cl. D10—109

FIG. 1

FIG. 2

FIG. 3

FIG. 4

FIG. 5

FIG. 1 is a front elevational view of a traffic sign for a school zone showing my new design;

FIG. 2 is a side elevational view of the sign shown in FIG. 1.

FIG. 3 is a rear elevational view of the sign shown in FIG. 1.

FIG. 4 is a top view of the sign shown in FIG. 1, and

FIG. 5 is a bottom view of the sign shown in FIG. 1.

The sign is shaded to indicate contrast. The indicia is shown in broken lines for illustrative purposes only.

I claim:

The ornamental design for a traffic sign for a school zone, as shown and described.
